UNITED STATES PATENT OFFICE.

JOSEPH T. ROBIN, OF NEW YORK, N. Y.

DESIGN FOR A SHOW-CASE.

No. 38,058.

Specification for Design.

Patented June 5, 1906.

Application filed April 3, 1906. Serial No. 309,708. Term of patent 7 years.

To all whom it may concern:

Be it known that I, JOSEPH T. ROBIN, a citizen of the United States, residing at New York city, (post-office address No. 258 Canal street,) in the borough of Manhattan, city, county, and State of New York, have invented a new, original, and ornamental Design for Show-Cases, of which the following is a specification, reference being had to the accompanying drawing, forming a part thereof,

and which represents in perspective a show-case embodying my design.

I claim—

The ornamental design for a show-case, as shown.

JOSEPH T. ROBIN.
